FIG. 1

FIG. 2

FIG. 3

FIG. 5

FIG. 4

FIG. 1 is a perspective view taken from the front and right side of the valve unit, embodying my new design.

FIG. 2 is a front elevational view thereof.

FIG. 3 is a bottom elevational view thereof.

FIG. 4 is a perspective view of a modification of FIG. 1 wherein the only difference resides in the tubular element projecting from the front end.

FIG. 5 is a fragmentary top plan view of the front end of the valve unit.

The valve unit shown in FIGS. 1-3 has the same appearance when viewed from the front and left side as it does in FIG. 1.

The appearance of the valve unit shown in FIG. 4 is the same when viewed from the front and left as that shown in FIG. 4.

The dominant features of the design reside in the portions shown in full lines in the drawings.

What I claim is:

The ornamental design for a valve unit, substantially as shown and described.
